(57) **CLAIM**

The ornamental design for a vehicle accessory base as shown and described.

DESCRIPTION

FIG. 1 is a top perspective view of a vehicle accessory base showing our new design;

FIG. 2 is a bottom perspective view thereof;

FIG. 3 is a top view thereof;

FIG. 4 is a bottom view thereof;

FIG. 5 is a first end view thereof;

FIG. 6 is a second end view thereof;

FIG. 7 is a first side view thereof; and,

FIG. 8 is a second side view thereof.

The broken lines in the drawings are included to show portions of the vehicle accessory base that form no part of the claimed design.
